FASTENER GUIDING ATTACHMENT FOR SEWING MACHINES

Victor Ostertag, Oshkosh, Wis., assignor to Union
Special Machine Company, Chicago, Ill., a cor-
poration of Illinois

Application May 14, 1949, Serial No. 93,364

12 Claims. (Cl. 112—136)

1

This invention pertains to sewing machines, and in one of its more specific aspects, to a sewing machine attachment mechanism adapted to guide elements of a slide fastener unit disposed along a line transverse to a line of stitching in the course of forming the stitching by the sewing machine needle and associated devices in a piece of work that includes the fastener unit.

While the mechanism of this invention is adapted to be advantageously employed in stitching together various arrangements of parts including a fastener unit in a piece of work, it is particularly useful in simultaneously sewing a waistband on a pair of trousers and securing an end of a slide fastener strip unit in place between the edge of the waistband and the edge of the main trouser body. At the time that the waistband is secured in such an arrangement of parts, the slide fastener unit is disposed transverse to the line of feed, that is, transverse to the line of stitching being formed by the sewing machine needle and associated elements, and is positioned between the waistband parts as the waistband passes the needle.

Experience has demonstrated that unless conventional metallic fastener elements of the fastener unit are properly guided as they are moved past the needle, the needle may strike one of the fastener elements, and as a consequence, the needle oftentimes is damaged or broken. Even if the needle is only slightly burred as a result of striking a fastener element, it will not thenceforth coact with other parts in the formation of proper stitches. This necessitates replacement of such needles and costly delays in production. Also, it is apparent that needle breakage due to striking a fastener element may endanger the operator.

The present invention obviates the foregoing difficulties as it properly guides fastener elements so as to permit the sewing machine needle to stitch across the fastener unit without striking any of such elements. To this end, the guiding mechanism of the invention comprises a device including a finger so constructed and arranged as to be readily swung into or out of service immediately in advance of the needle for guiding the fastener elements at the proper time in the course of forming stitches across the unit. The finger, when in operative position, engages and guides adjacent fastener elements, but permits the needle to pass between those elements. The device is adapted to be placed into and out of service at the will of the operator, and is in-

2

tended to be in active service only for the interval or a portion of the interval of time during which the fastener unit is being fed past the needle. At other times, the device is swung to an inactive or inoperative position away from the stitch-forming devices, thereby permitting the carrying out of conventional sewing operations without interfering with or obstructing the work or retarding normal operations.

A primary object of the invention is to expedite the joining together of a slide fastener unit and other parts along a line across the fastener unit.

Another object of the invention is to provide a sewing machine attaching mechanism adapted to facilitate the formation of a line of stitches across a slide fastener unit in the course of stitching together parts of a piece of work including the fastener unit.

Another object of the invention is to provide an attaching mechanism of the character indicated, that is adapted to be readily placed into and out of active service at the will of the operator.

Another object of the invention is to minimize the possibility of damage or breakage to a sewing machine needle or associated devices in the course of forming stitches across a slide fastener unit.

The invention has for another object the provision of a sewing machine slide fastener guiding attachment that may be readily and quickly mounted on or removed from a sewing machine.

A further object of the invention is to provide a mechanism of the character indicated, that is adapted to perform its intended functions in an effective and trouble-free manner.

A further object of the invention is to provide a sewing machine slide fastener guiding mechanism that is relatively simple in design, sturdy in construction and reasonable in manufacturing and maintenance costs.

The foregoing objects, together with other objects, as well as the advantages obtainable by the practice of this invention, will be readily understood by persons skilled in the art upon reference to the following detailed description, taken in conjunction with the annexed drawings, which respectively describe and illustrate a preferred arrangement of devices embodying the invention.

50 In the drawings:

Figure I is a view in front elevation of a flat bed sewing machine having an arrangement of devices embodying the invention operatively associated therewith, certain parts that are not

essential to a full understanding of the invention being omitted, and certain other parts being broken away for better illustration;

Figure II is an enlarged view in end elevation of the apparatus of Figure I, as seen from the left thereof, the presser foot and a portion of the needle bar being omitted for better illustration of other parts;

Figure III is a top plan view of Figure I, a portion of the overhanging arm of the sewing machine and certain other parts shown in Figure I being removed for better illustration of devices mounted on the work support of the sewing machine;

Figure IV is an enlarged fragmentary view in side elevation of Figure I, as observed from the left thereof, and illustrates the cooperative relationship of the presser foot, the needle and the guide finger of the guiding mechanism;

Figure V is an enlarged fragmentary view of Figure III and shows one relative position of certain parts in the course of feeding a piece of work through the sewing machine;

Figure VI corresponds to Figure V and shows another relative position of the parts illustrated therein; and

Figure VII is an enlarged view in vertical cross section taken along line 7—7 of Figure V.

Referring now to the drawings wherein like reference numerals denote corresponding parts through the several views, and more particularly to Figures I and II, I have illustrated therein a flat bed type sewing machine, generally indicated by numeral 10 and comprising a base 11, the top of which is planar and constitutes a work support 12. Extending upwardly of the base is a hollow standard 13 that carries an integral hollow overhanging arm 14 having a depending head 15. Vertically reciprocable within head 15 is a needle bar 16 to which is removably attached a conventional needle 17. A sewing machine of this general type is disclosed in F. F. Zeier Patent 1,843,188, entitled "Sewing Machine," to which reference may be had for an understanding of an arrangement of devices, not shown herein, for driving needle 17.

Parallel to needle bar 16 is a presser bar 20 that carries an open-toed presser foot 21 at its lower end. As is best shown in Figures VI and VII, the presser foot is provided with an elongated slot 22 that extends rearwardly of its front edge 23. Mounted on overhanging arm 14 for yieldingly urging presser bar 20 and, therefore, presser foot 21 downwardly is a presser mechanism 24 which includes a horizontally disposed leaf spring 25. One end of the leaf spring is secured to the overhanging arm by an anchoring stud 26 (Figure III). A thumb nut 27 engages a threaded vertical stem 28 which is attached to overhanging arm 14 and extends through a central aperture in the leaf spring. Reference may be had to F. A. Kucera Patent 2,103,470, entitled "Presser Mechanism for Sewing Machines," for further details as to the construction and operation of the presser mechanism herein illustrated.

A feed dog 30 is positioned in base 11 directly below presser foot 21, and is encompassed by a throat plate 31 (Figure III). The feed dog is preferably actuated by a mechanism 32 of the four-motion type that may be the same as or similar to the feeding mechanism illustrated and described in A. J. Wohlpert Patent 1,817,727, entitled "Feeding Mechanism for Sewing Machines."

The sewing machine may be mounted in the

usual manner on a horizontally disposed top 33 of a suitable supporting structure not otherwise shown. Top 33 is provided with a through aperture 34.

An arrangement of devices that constitutes a recommended form of fastener guiding attachment mechanism constructed in accordance with this invention will now be described, reference being had initially to Figures I and III. In this connection, a cloth plate cover or support 35 is mounted on base 10 immediately adjacent throat plate 31 and is detachably secured to the base by a latch 36. Attached to cover plate 35 by screws 37 is a second plate 38. A bracket 40 is secured to plate 38 by a pair of screws 41 and is provided with a pair of spaced-apart parallel arms 42 that support a freely rotatable stub shaft 43. A member or lever 44 engages stub shaft 43 and is secured thereto by a set screw 45. As will be apparent from an examination of Figure III, lever 44 is pivotal about the axis of stub shaft 43, which axis is normal to the path of reciprocation of needle 17.

A fastener guiding device 46 is pivotal about the axis of a stud screw 47 that is attached to the free end of lever 44, and that is normal to the axis of stub shaft 43. Guiding device 46 includes a body 50 formed with a stop shoulder 51 and a series of teeth 52, arranged along an arc of a circle that is concentric with the axis of stud screw 47. Integral with body 50 is a generally hook-shaped member 53 that terminates in a tapered wedge-like guide finger 54 (Figures II and IV).

Lever 44 is provided at its free end with an upstanding extension 55 which carries a stop screw 56 for adjustably limiting pivotal movement of device 46 in a clockwise direction, as viewed in Figure V. The stop screw is maintained in preselected position by a lock nut 57. The upper or free end portion of extension 55 projects laterally and is positioned immediately above a horizontal arm 58 that is attached to a collar 59 which is carried by presser bar 20 (Figures I, II and IV). This arrangement permits the raising of lever 44 and, therefore, guiding device 46 simultaneous with the raising of the presser bar and presser foot 21.

A bell crank or arm 60 is pivotally connected to lever 44 by a stud screw 61 and is provided at one end with an arcuate rack 62, the teeth of which mesh with teeth 52 of device 46, whereby pivotal movement of the bell crank about stud screw 61 imparts corresponding pivotal movement of device 46 about its stud screw 47. A laterally extending arm 63 is attached to lever 60 by screws 64. A spring 65 is connected at one end to arm 63 and at its other end to a pin 66 carried by plate 38. This spring is stressed in tension and normally urges bell crank 60 in a clockwise direction of rotation, as viewed in Figure III. A stop pin 67, extending upwardly from plate 38, limits clockwise rotation of bell crank 60, as viewed in Figure III. An upright post 70 is affixed to plate 38 and extends through and beyond a slot 71 in lever 44. Post 70 is threaded at its upper end to engage a knurled thumb nut 72. A helical spring 73 concentric with post 70 bears at its opposite ends against lever 44 and thumb nut 72 to normally and yieldingly urge lever 44 and the devices mounted thereon in a downward direction about the axis of stub shaft 43.

Bell crank 60 is adapted to be rotated about pivot screw 61 in a counter-clockwise direction,

as viewed in Figure III, to raise lever 44 and thereby raise guiding device 46.

as viewed in Figure III, through the coaction of devices that will next be described. Referring to Figures I and II, such devices include a block 74 supported on top 33 and having a vertical through aperture 75 that is in alignment with aperture 34 in the top. A pulley bracket 76, consisting of a base 77 and a pair of parallel spaced arms 78, is attached to the block by screws 79. Disposed between bracket arms 78 and rotatable about a pin 80 carried by these arms is a pulley 81.

An inverted U-shaped bracket 82 is mounted against the under surface of top 33 and includes a pair of spaced parallel arms 83 which support a rock shaft 84. A collar 85 is attached to each end of the rock shaft to prevent axial movement of the shaft. A pair of blocks 86 and 87 embrace the rock shaft intermediate bracket arms 83 and are angularly and axially adjustable with respect to the rock shaft through the medium of set screws 88 and 89, respectively. Extending radially of block 86 is a rod 90. A flexible cable 91 is connected at one end to the free end of rod 90, extends upwardly through apertures 34 and 75, passes over pulley 81, and is connected at its other end to bell crank 60. A second rod 93 is attached to block 87 by a set screw 94. A knee pad member 95 is adjustably attached to the lower end portion of rod 93 by a set screw 96.

As is best shown in Figures V and VI, a roller 100 is freely rotatable about a horizontally disposed stud screw 101 that is carried by the free end portion of arm 63. A cam member 102, having a camming upper surface 103, is mounted on plate 38 by screws 104 (Figure II). The roller is adapted to bear against the upper surface of plate 38 when the parts are in the relative position shown in Figure V, and to ride upwardly along camming surface 103 in the course of movement of bell crank 60 from the position shown in Figure V to that shown in Figure VI.

I have shown in Figures V and VI a portion of the fabric of a trouser body 105 including a fly strip 106. Secured to strip 106 by rows of stitching 107 is a conventional slide fastener unit 108 consisting of a tape stringer 109 and a series of fastener elements 110. A preformed fabric unit 111 (Figures VI and VII) comprises a waistband 112 stitched to a waistband lining strip 113 and to a waistband reinforcing strip 114, as indicated at 115. Reinforcing strip 114 is superposed on lining strip 113, a portion 116 of the lining strip being folded over the reinforcing strip and secured thereto by a row of stitching 117. In Figure VI there is shown a belt loop 118 secured to the waistband.

For the purpose of briefly outlining the mode of operation of the illustrated apparatus, it is assumed that the same is being used to join fabric unit 111 to trouser body 105 and that fastener unit 108 and the other parts of the piece of work are in the relative position shown in Figure V. The line of stitching being formed by the sewing machine is indicated at 120, and as is shown in Figure VI, this line of stitching is transverse to the fastener. It is further assumed that the parts of the guiding mechanism are in the relative position shown in Figure VI. This is the normal position of the parts of the guiding mechanism due to the action of spring 65. With the parts in this position, lever 44 has been raised to its uppermost position about its pivotal connection with bracket 40 and guiding device 46 has been pivoted to inactive position about pivot stud 47.

In the course of stitching unit 111 to body 105, the guiding mechanism is maintained out of service until fastener elements 110 approach the needle. At that time the operator presses pad member 95 with his knee, imparting counter-clockwise pivotal movement to rock shaft 84 (Figure I) and actuating flexible cable 91 so as to impart counter-clockwise rotation to bell crank 60 about pivot stud 61 against the action of spring 65, thereby imparting clockwise rotation to guiding device 46 about its pivotal stud 47. Simultaneous with the foregoing, roller 100 rides downwardly along cam 102 and lever 44 is swung in a downward direction. It will thus be noted that actuation of the knee pad member 95, as indicated, results in a combined downward and pivotal movement of guiding device 46 and, therefore, finger 54. The finger is so constructed and arranged that as it moves downwardly and arcuately, it enters in the space between adjacent fastener elements 110 and aligns this space with the needle. As the work is continued to be fed through the sewing machine, the needle passes between the aforementioned adjacent fastener elements. After the fastener unit and associated fabrics have been fed past the needle, the operator releases knee pressure on pad member 95, whereupon the parts of the attachment mechanism are returned to inactive position (Figure VI) by spring 65.

Thus it will be seen that the construction herein shown and described is well adapted to accomplish the objects of the present invention. It will be understood, however, that the invention may be embodied otherwise than here shown, and that in the form illustrated certain obvious changes in construction may be made. Therefore, I do not wish to be limited precisely to the construction herein shown except as may be required by the appended claims considered with reference to the prior art.

I claim:

1. In a sewing machine attachment mechanism that is adapted to guide fastener elements of a slide fastener unit disposed along a line generally transverse to a line of stitching in the course of forming such stitching by the sewing machine needle and associated elements in a piece of work which includes the fastener unit, a support adapted to be mounted on the sewing machine, a lever pivotally connected to the support, a fastener guiding device including a finger having a free end and pivotally connected to the lever, means connected to the lever for moving the lever and the device in directions about said pivotal connections to position the free end of the finger adjacent and to the side of the needle opposite previously formed stitches, and means connected to the lever for moving the lever and the device in reverse directions about said pivotal connections to position the free end of the finger away from the needle.

2. In a sewing machine attachment mechanism that is adapted to guide fastener elements of a slide fastener unit disposed along a line generally transverse to a line of stitching in the course of forming such stitching by the sewing machine needle and associated elements in a piece of work which includes the fastener unit, a support adapted to be mounted on the sewing machine, a lever pivotally connected to the support, a fastener guiding device including a finger having a free end and pivotally connected to the lever, means normally and simultaneously urging the lever in one direction about its pivotal connec-

tion with the support and the device in a corresponding direction about its pivotal connection with the lever to position the free end of the finger away from the needle and above the work, and means connected to the lever for moving the lever and device in reverse directions about said pivotal connections against the action of said first-mentioned means to swing the free end of the finger toward the work and to the side of the needle opposite previously formed stitches.

3. In a sewing machine attachment of the class described, a support adapted to be mounted on the sewing machine, a lever pivotally connected to the support, first means for normally urging the lever in one direction about its pivotal connection with the support, a fastener guiding device pivotally connected to the lever, said device including a finger having a free end, second means for normally urging the device in one direction about its pivotal connection with the lever, and means connected to the lever for simultaneously moving the lever and device in reverse directions about corresponding pivotal connections against the action of the first and second means.

4. In an attachment mechanism for a sewing machine which has a reciprocable needle, a lever adapted to be mounted on the sewing machine and pivotal about a first axis that is generally normal to the path of reciprocation of the needle, first means for normally urging the lever in one direction about said first axis, a fastener guiding device carried by and pivotal with respect to the lever about a second axis normal to said first axis, said device including a finger having a free end disposed to the side of said second axis remote from said first axis, second means for normally urging the device in one direction about said second axis, and means for simultaneously moving the lever and the device in reverse directions about said first and second axes, respectively, against the action of said first and second means.

5. In an attachment mechanism for a sewing machine which has a reciprocable needle, a lever adapted to be mounted on the sewing machine and pivotal about a first axis that is generally normal to the path of reciprocation of the needle, a fastener device carried by and pivotal with respect to the lever about a second axis normal to said first axis, said device including a finger having a free end disposed to the side of said second axis remote from said first axis, means normally and simultaneously urging the lever in one direction about said first axis and the device in a corresponding direction about said second axis to position the free end of the finger away from the needle, and means for moving the lever and the device in reverse directions about said axes against the action of said first-mentioned means to swing the free end of the finger toward the needle.

6. An attachment mechanism of the character described comprising a support, a lever pivoted to the support about a first axis, a guiding device pivoted to the lever about a second axis, and means for normally and simultaneously imparting pivotal movement to the lever in one direction about said first axis and to the device in a corresponding direction about said second axis, said means comprising an arm pivoted to the lever about a third axis, means for normally imparting movement to the arm in one direction about said third axis and means responsive to movement of the arm in said one direction for

imparting movement to the lever and to the device in said one direction and corresponding direction, respectively.

7. An attachment mechanism of the character described comprising a support, a lever pivoted to the support about a horizontal first axis, a guiding device pivoted to the lever about a second axis normal to said first axis, and means for normally and simultaneously imparting pivotal movement to the lever in one direction about said first axis and to the device in a corresponding direction about said second axis, said means comprising an arm pivoted to the lever about a third axis that is parallel to said second axis, means for normally imparting movement to the arm in one direction about said third axis and means responsive to movement of the arm in said one direction for imparting movement to the lever and to the device in said one direction and corresponding direction, respectively.

8. An attachment mechanism of the character described comprising a support, a lever pivoted to the support about a horizontal first axis, a guiding device pivoted to the lever about a second axis normal to said first axis, an arm pivoted to the lever about a third axis parallel to said second axis and intermediate said first and second axes, resilient means for normally imparting movement to the arm in one direction about said third axis, means responsive to movement of the arm in said one direction for swinging the lever upwardly about said first axis and for imparting pivotal movement to the device in one direction about said second axis, and means operable against the action of the resilient means for simultaneously imparting downward movement to the lever about said first axis and pivotal movement to the device in a reverse direction.

9. An attachment mechanism of the character described comprising a support, a lever disposed above and having one end pivoted to the support about a first axis, means for normally urging the lever in one direction about said first axis, a guiding device pivoted to the other end of the lever about a second axis, an arm pivoted to the lever about a third axis parallel to said second axis and intermediate said first and second axes, resilient means for normally imparting movement to the arm in one direction about said third axis, means including camming means responsive to movement of the arm in said one direction for swinging the lever in a reverse direction about said first axis against the action of said first-mentioned means and for imparting pivotal movement to the device in one direction about said second axis, and means operable against the action of the resilient means for simultaneously imparting movement to the lever about said first axis in said one direction and pivotal movement to the device in a reverse direction.

10. An attachment mechanism of the character described comprising a support, a lever disposed above and having one end pivoted to the support about a horizontal first axis, means for normally urging the lever downwardly about said first axis, a guiding device pivoted to the other end of the lever about a second axis normal to said first axis, an arm pivoted to the lever about a third axis parallel to said second axis and intermediate said first and second axes, resilient means for normally imparting movement to the arm in one direction about said third axis, means responsive to movement of the arm in said one direction for swinging the lever upwardly about

said first axis against the action of said first-mentioned means and for imparting movement to the device in one direction about said second axis, and means operable against the action of the resilient means for simultaneously imparting downward movement to the lever about said first axis and pivotal movement to the device in a reverse direction.

11. An attachment mechanism of the character described comprising a support, a lever disposed above and having one end pivoted to the support about a horizontal first axis, means for normally urging the lever downwardly about said first axis, a guiding device pivoted to the other end of the lever about a second axis normal to said first axis, an arm pivoted to the lever about a third axis parallel to said second axis and intermediate said first and second axes, resilient means for normally imparting movement to the arm in one direction about said third axis, means responsive to movement of the arm in said one direction for swinging the lever upwardly about said first axis against the action of said first-mentioned means and for imparting movement to the device in one direction about said second axis, a first stop member carried by the support for limiting pivotal movement of the device in said one direction, means operable against the action of the resilient means for simultaneously imparting downward movement to the lever about said first axis and pivotal movement to the device in a reverse direction, and a second stop member carried by the lever for limiting pivotal movement of the device in said reverse direction.

12. In a sewing machine attachment mech- 35

of a slide fastener unit disposed along a line generally transverse to a line of stitching in the course of forming such stitching by the sewing machine needle and associated elements in a piece of work which includes the fastener unit, a support adapted to be mounted on the sewing machine, a fastener guiding device connected to the support and including a finger having a free end, said device being pivotal with respect to the support about a substantially vertical axis, means connected to the device for moving the device in one direction about its pivotal connection with the support to position the free end of the finger adjacent to the side of the needle opposite previously formed stitches, and means connected to the device for moving the device in a reverse direction about its pivotal connection with the support to position the free end of the finger away from the needle and above the fastener unit, said last mentioned means including a stationary cam.
